FORMYLMETHYLENE DERIVATIVES

Leslie G. S. Brooker, Rochester, N. Y., assignor,
by mesne assignments, to Eastman Kodak
Company, Jersey City, N. J., a corporation of
New Jersey

No Drawing. Application August 13, 1936, Serial
No. 95,925. In Great Britain August 15, 1935

10 Claims. (Cl. 260—289)

This invention relates to formylmethylene derivatives and a process for the preparation thereof. The formylmethylene derivatives with which this invention is concerned can be formulated as follows:—

and

Wherein D represents a vinylene or a phenylene group, R represents an organic residue and Y represents the non-metallic atoms necessary to complete a heterocyclic nucleus selected from the group consisting of five-membered and six-membered heterocyclic nuclei. More particularly, R can be an alkyl group, such as methyl, ethyl, n-butyl or n-decyl and the five-membered heterocyclic nucleus can be a thiazole nucleus, such as thiazole, 4-phenylthiazole, benzothiazole or naphthothiazole, an oxazole nucleus, such as benzoxazole or naphthoxazole, a selenazole nucleus such as benzoselenazole, a thiazoline nucleus or a selenazoline nucleus and the six-membered heterocyclic nucleus can be a pyridine, or a quinoline nucleus, such as 5-methyl quinoline or a benzoquinoline nucleus.

I have found these formylmethylen derivatives can be prepared by hydrolyzing a β -anilino derivative of a heterocyclic quaternary salt, i. e., derivatives which can be represented by the following formula:

and

Wherein D represents a vinylene or a phenylene group, R represents an alkyl group, R' represents an aryl group of the benzene or naphthalene series, X represents an acid radical, Y represents the non-metallic atoms necessary to complete a five-membered or six-membered heterocyclic nucleus and Z represents hydrogen or an acyl group. More particularly, R can be an alkyl group, such as methyl, ethyl, n-butyl or n-decyl, X can be an acid radical such as halide, alkylsulfate, p-toluenesulfonate or perchlorate, the five-membered heterocyclic nucleus can be a thiazole nucleus, such as 4-methylthiazole, 4-phenylthiazole, benzothiazole or naphthothiazole, a selenazole nucleus, such as selenazole or benzoselenazole, an oxazole nucleus, such as benzoxazole or naphthoxazole, a thiazoline nucleus, a selenazoline nucleus, or an indolenine nucleus,

such as a 3,3-dialkylindolenine nucleus, and the six-membered heterocyclic nucleus can be a pyridine, a quinoline or a benzoquinoline nucleus. Z can be hydrogen, acetyl, propionyl, benzoyl, naphthoyl or the like. R' can be phenyl, naphthyl, tolyl, p-chlorophenyl or the like.

The nature of my new process can be illustrated by the following chemical equation depicting the alkaline hydrolysis of 2-(β -anilino-vinyl)- β -naphthothiazole ethiodide:

The liberated hydrogen iodide is probably bound as sodium iodide by the sodium hydroxide. The process is advantageously carried out in alkaline media. Sodium and potassium hydroxides and sodium and potassium carbonates being particularly useful alkalies. Heating accelerates the reactions. The hydrolysis can also be carried out in acid media. Strong acids, such as hydrochloric, sulfuric or trichloroacetic, are advantageously employed. Acid reacting inorganic salts can be used. In acid media the course of the reaction can probably be illustrated as follows:

My new process is especially well adapted to the production of formylmethylen derivatives from benzoxazole, benzothiazole, naphthothiazole, naphthoxazole, benzoselenazole and quinoline β -anilino derivatives. The following examples serve to illustrate but are not intended to limit my invention.

Example 1—1-ethyl-2-formylmethylen-β-naphthothiazoline

2-(β-anilinovinyl)-β-naphthothiazole ethiodide was prepared by fusing an intimate mixture of 2-methyl-β-naphthothiazole ethiodide (21 g.; 1 mol.) with diphenylformamidine (13.2 g.; 2 mol., i. e., 100% excess) at 150° C. for about 10 minutes. The product was crushed and washed with acetone.

10 4.6 g. (1 mol.) of 2-(β-anilinovinyl)-β-naphthothiazole ethiodide was hydrolyzed by refluxing it for about 15 hours in 50 cc. of 95% ethyl alcohol with 50 cc. of 40% aqueous sodium hydroxide. The reaction mixture separated into 15 two layers when cold and the alcoholic layer was separated off and concentrated to small bulk. The gummy semi-solid residue became crystalline on stirring with a little ether. After washing with water, recrystallization was effected 20 from n-propyl alcohol. The recrystallized product melted at 157-160° C. with decomposition.

Example 2—2-methyl-1-formylmethylen-benzothiazoline

25 1.5 g. (1 mol.) of 1-(β-acetanilidovinyl)-benzothiazole methiodide was hydrolyzed by boiling over a free flame with 50 cc. of hydrochloric acid (1 volume of hydrochloric acid, sp. g. 1.18 with 1 volume of water). After evaporating to dryness, 30 the residue was made alkaline with potassium carbonate and extracted with ether. The combined extracts gave a residue which was oily and did not lend itself to crystallization readily. It behaved like the above formylmethylen derivative 35 in its reaction.

Example 3—2-formylmethylen-1-methyl-1,2-dihydroquinoline

3.9 g. (1 mol.) of 2-(β-anilinovinyl)-quinoline 40 methiodide was heated on the steam bath for about 15 minutes with 30 cc. of 95% ethyl alcohol and 30 cc. of 20% aqueous sodium hydroxide. Two layers separated on cooling and the alcoholic layer was concentrated nearly to dryness. The sticky residue was dissolved in ether. The 45 other solution dried and the solution concentrated. Solid separated from the concentrate on cooling. It was recrystallized from n-propyl alcohol yielding brownish crystals melting at 87-90° C.

50 *Example 4—2-ethyl-1-formylmethylen-benzoxazoline*

4.3 g. (1 mol.) of 2-(β-acetanilidovinyl)-benzoxazole ethiodide was refluxed for about 2 hours 55 with 25 cc. of 95% ethyl alcohol and 10 cc. of water containing 4.0 g. of sodium carbonate. Water (300 cc.) was then added and the whole extracted with ether. On drying the ether solution and evaporating a brownish viscous residue was obtained. The product did not lend itself to ready crystallization but gave the characteristic reactions of formyl-methylen derivatives.

60 In a similar manner other β-anilino derivatives can be hydrolyzed to produce formylmethylen derivatives. β-acetanilido, β-propionanilido, β-benzanilido or the like derivatives can be used. β-anilinovinyl derivatives can be prepared as illustrated in Example 1. Further description is provided in British Patent 344,409.

65 These herein-described formylmethylen derivatives can be used for the preparation of merocarbocyanine dyes by condensation with heterocyclic compounds containing a reactive methyl-70 ene group, for example 2-thio-2,4-(3,5)-thi-

azolediones. See the copending application of Leslie G. S. Brooker Serial No. 95,926 filed August 13, 1936. These herein-described formylmethylen derivatives can also be used to prepare carbocyanine dyes by condensing with cyclammonium quaternary salts containing a reactive methyl group. Condensations are advantageously carried out in the presence of a water-binding agent, e. g., acetic anhydride.

What I claim as my invention and desire to be secured by Letters Patent of the United States of America is:

1. A product characterized by the following formula:

wherein A represents a naphthylene group and R represents an alkyl group.

2. A product characterized by the following formula:

wherein R represents an alkyl group.

3. A product characterized by the following formula:

4. A process comprising hydrolyzing a compound characterized by one of the following formulas:

and

wherein D represents a radical selected from the group consisting of vinylene and phenylene groups, R represents an alkyl group, R' represents an aryl group, X represents an acid radical, Y represents the non-metallic atoms necessary to complete a heterocyclic nucleus selected from the group consisting of five-membered and six-membered heterocyclic nuclei and Z represents a substituent selected from the group consisting of hydrogen and an acyl group.

5. A process comprising hydrolyzing, in the presence of a basic substance, a compound characterized by one of the following formulas:

and

wherein D represents a radical selected from the group consisting of vinylene and phenylene groups, R represents an alkyl group, R' represents an aryl group, X represents an acid radical, 5 Y represents the non-metallic atoms necessary to complete a heterocyclic nucleus selected from the group consisting of five-membered and six-membered heterocyclic nuclei and Z represents a substituent selected from the group consisting of 10 hydrogen and an acyl group.

6. A process comprising hydrolyzing, in the presence of an acidic substance, a compound characterized by one of the following formulas:

and

wherein D represents a radical selected from the group consisting of vinylene and phenylene 25 groups, R represents an alkyl group, R' represents an aryl group, X represents an acid radical, Y represents the non-metallic atoms necessary to complete a heterocyclic nucleus selected from the group consisting of five-membered and six- 30 membered heterocyclic nuclei and Z represents a substituent selected from the group consisting of hydrogen and an acyl group.

7. A process comprising hydrolyzing, in the presence of an alkali, a compound characterized by one of the following formulas:

and

wherein D represents a radical selected from the group consisting of vinylene and phenylene groups, R represents an alkyl group, R' represents an aryl group, X represents an acid radical, Y represents the non-metallic atoms necessary to complete a heterocyclic nucleus selected from the group consisting of five-membered and six-membered heterocyclic nuclei and Z represents an acyl group. 15 20

8. A process comprising hydrolyzing, in the presence of an alkali, a β -anilinovinyl-naphtho-thiazole alkyl quaternary salt.

9. A process comprising hydrolyzing, in the presence of an alkali, a β -anilinovinyl- β -naphtho-thiazole alkyl quaternary salt. 25

10. A process comprising hydrolyzing, in the presence of an alkali, a β -anilinovinyl-quinoline alkyl quaternary salt. 30

LESLIE G. S. BROOKER.
